UNITED STATES PATENT OFFICE.

LESTER S. KUBIAC, OF YOUNGSTOWN, OHIO.

ELECTRIC-ARC LAMP.

Application filed November 9, 1926. Serial No. 147,206.

This invention relates to arc lamps, and more particularly to the multiple type of lamp, the primary object being to provide what may be termed an under-slung construction, involving a clutch carrying bar or bracket common to both carbons (which we believe to be entirely new in the art), and to so mount and equip this bar as to avoid any sudden or abrupt starting or stopping of the same by reason of the more or less unavoidable violent movement of the armature in the solenoid, thus effecting an absolutely uniform operation or movement of the carbons, as well as a slow, gentle separation of the same and building up of the arc, and also avoiding the more or less noisy and disagreeable sputtering and snapping usually caused by the separation of the carbons.

While, so far as I am aware, the arc lamps now in use are all operated through a more or less complex system or series of levers, bell-cranks, walking beams, etc., mounted above the solenoid, I am aware that various attempts at under-slung control have been made, but without satisfactory results so far as my observations go.

A practical embodiment of my invention is shown in the accompanying drawings, in which Fig. 1 is a front elevation; Fig. 2 is an end elevation with the case shown in section; Fig. 3 is a rear elevation disclosing the rheostat, or resisting elements, disposed outside of the case enclosing the arcs or lights; Fig. 4 is a plan view partially in section on line 4—4 Fig. 1, showing the rheostat and wire diagram; Fig. 5 is a fragmentary view, showing in detail the general arrangement and assembly of the various parts and elements of the operating mechanism; and Fig. 6 is a fragmentary view, showing in detail the spring controlled bar 28 mounted on the bolts 25—25.

I house the mechanism of my device in what may be termed an open supporting frame, designated generally as F, and consisting of the top plate, or cap, 1, the bottom plate, or base, 2, the back wall 3, the upright corner posts 4—4, which tie the top and bottom plates 1 and 2 together, and the two intermediate columns or posts 5—5, also rigidly secured to the top and bottom plates of the frame.

Mounted upon the posts 5—5, intermediate their ends, is the plate 6, and the solenoid 7 is securely held in inverted position be-

tween this plate and the top plate 1 of the frame by means of the bolts 8—8.

Also, slidably mounted upon the posts 5—5, by means of the relatively long tubular bearing guides 9—9, is the clutch bar or bracket 10 provided with oppositely disposed lateral extensions 11 and 12 (see Fig. 4), and carrying at each end the clutch elements 13 and 14 adapted to engage the upper carbon 15.

The use of the clutch bar 10 being common to both carbons, and being provided with its long guide bearings, insures absolutely synchronous movement of the carbons as well as absolute alignment of travel of the same.

Secured to the upper face of the clutch bar 10 are the ordinary dash-pots 16—16, and the dash-pot piston stem 17 is swingingly secured to the upper face of the bottom plate 2 of the frame.

Rigidly secured to the upper face of the bottom plate 2 is the post 18, provided at its upper end with a slot within which the counter-weight lever 19 is pivoted by the pin 20. This lever carries at one end the counter-weight 21, while at its opposite end it is provided with a transverse slot for a purpose to be stated in the following paragraph.

Rigidly secured to the extension 11 on the clutch plate 10 is the post 22, provided at its upper end with a slot 23 and also with a pin 24 passing through the slot and adapted to be engaged by the slotted end of the lever 19 pivoted in the post 18 as hereinbefore explained.

Also rigidly secured to each of the extensions 11 and 12 on the clutch bar 10 is a bolt or pin 25 provided at its upper end with a head 26, and upon which is mounted a coil spring 27.

Slidably mounted upon bolts 25—25, and beneath the coil spring 27—27, is a flat bar 28 provided with counter-bores 29—29 for the reception of the lower ends of the springs 27—27, designed to prevent contact or friction between the bar and the bolts. (See Fig. 6.)

The armature stem 30 carries at its lower end a cross-head or yoke 31 which is securely fastened to the bar 28 by means of rivets 32—32. Fig. 4.

Obviously, an exact mechanical equivalent to this construction would be to make the cross-head or yoke 31 longer and mount it directly upon the bolts 25—25, thus doing 110

away with the bar 28 entirely. But this is merely a matter of convenience in manufacture.

Slidably mounted upon the corner posts 5 4-4 of the frame are the oppositely disposed carbon holders 33-33 to which the upper carbons 15-15 are secured by screws 34-34.

For the purpose of insulating the carbons 10 and operating elements from the frame of the device, I use the plates or sheets 35-35 of asbestos or other suitable material. Fig. 5.

Firmly secured to, and suspended from, the bottom plate or base 2 of the frame is 15 the supporting rod 36, carrying at its lower end an adjustable cross-bar 37 having a relatively long tubular guide bearing 38 held in position by the screw 39, said cross-bar being provided at each end with a carbon 20 holder 40 to which the lower carbons 41-41 are secured by screws 42-42.

The rheostat, or resistance elements, is 25 represented by 43, and 44 indicates the ordinary shunt switch to regulate the strength of the current passing through the rheostat.

The operation of my device, briefly stated, is substantially as follows:

When the solenoid is energized, the armature 30 will travel upwardly in the solenoid, carrying with it the bar 28 against the pressure of the springs 27-27, but without moving the bar 10 until the compression of the springs is sufficient to overcome the 35 gravity resistance of the bar 10, the clutch elements and the carbons, and the resistance of the dash pots, less the gravity weight of the counter-weight 21 (which will then move downwardly), at which time the bar 10 will 40 move upwardly, and the clutch elements carried by the bar will lift the upper carbons, separating them from the lower carbons, and start the building up of the arc.

It is obvious that in this operation, by 45 reason of the action of the springs 27-27, the separation of the carbons will be slower and more gentle than if accomplished directly from the sudden starting of the armature.

The relative movement of the various operating elements are so adjusted that when 50 the armature reaches what is known as the point of magnetic balance in the solenoid, the arc will be of proper length for service.

As the carbons burn away, however, the 55 length of the arc gradually increases and the strength of the current will correspondingly decrease until the magnetic strength of the solenoid is no longer sufficient to 60 carry its load, at which time the armature will begin to drop, thus permitting the clutch bar 10 to fall, but under the cushioning effect of the springs 27-27, and gently retarded, also, by the gravity resistance of 65 the weight 21 (which will then move up-

wardly), until the clutch element 14 comes in contact with the insulating plate or sheet 35, which will release its grip upon the upper carbon and permit the latter to fall until it again comes in contact with the lower 70 carbon, thus, theoretically, eliminating the arc and extinguishing the light, although the operation is so rapid that this fact is not perceptible to the eye. When the two carbons come in contact the circuit is closed, 75 the current again flows to, and energizes, the solenoid, and this cycle of operation is repeated as long as the lights are burning.

As already indicated, it is believed that the use of a single lifting bar, carrying 80 clutch elements for both carbons, is entirely new in the art.

I claim:

1. In an arc lamp, a carbon control mechanism consisting of a horizontal lifting bar 85 slidably mounted upon upright supports and carrying at each end clutch elements adapted to engage the carbon, and means for actuating said lifting bar.

2. In an arc lamp, a carbon control mechanism consisting of a horizontal lifting bar 90 slidably mounted upon upright supports and carrying at each end clutch elements adapted to engage the carbon, and a solenoid unit for actuating said lifting bar.

3. In an arc lamp, a carbon control mechanism consisting of a horizontal lifting bar 95 slidably mounted upon upright supports and carrying at each end clutch elements adapted to engage the carbon, and a solenoid unit for actuating said lifting bar, the armature stem of said solenoid unit having a yielding connection with said lifting bar.

4. In an arc lamp, a carbon control mechanism consisting of a horizontal lifting bar 100 slidably mounted upon upright supports and carrying at each end clutch elements adapted to engage the carbon, a solenoid unit for actuating said lifting bar, the armature stem of said solenoid being provided at its outer 105 end with a cross-head slidably mounted upon headed bolts carried by said lifting bar, and a coil spring mounted upon each of said bolts between its head and said cross-head.

5. In an arc lamp, a carbon control mechanism consisting of a horizontal lifting bar 110 slidably mounted upon upright supports and carrying at each end clutch elements adapted to engage the carbon, and means for actuating said lifting bar, said actuating means including a lever fulcrumed intermediate its ends, and carrying at one end a counter-weight and at its other end having a loose engagement with said lifting bar.

6. In an arc lamp, a carbon control mechanism consisting of a horizontal lifting bar 115 slidably mounted upon upright supports and carrying at each end clutch elements adapted to engage the carbon, and means for actuating said lifting bar, said actuating means 120 including a lever fulcrumed intermediate its ends, and carrying at one end a counter-weight and at its other end having a loose engagement with said lifting bar.

consisting of a solenoid unit, and a lever fulcrumed intermediate its ends, and carrying at one end a counter-weight and at its other end having a loose engagement with said lifting bar.

7. In an arc lamp, a carbon control mechanism consisting of a horizontal lifting bar slidably mounted upon upright supports and carrying at each end clutch elements adapted 10 to engage the carbon, and means for actuating said lifting bar, said actuating means con-

sisting of a solenoid unit, the armature stem of said solenoid having a yielding connection with said lifting bar, and a lever fulcrumed intermediate its ends and carrying at one end a counter-weight and at its other end having a loose engagement with said lifting bar. 15

In testimony whereof I hereunto affix my signature.

LESTER S. KUBIAC.
